(57) **CLAIM**

The ornamental design for a sealable snack container, as shown and described.

DESCRIPTION

FIG. 1 is a perspective view of a first embodiment of a sealable snack container in an open position showing my new design;

FIG. 2 is a top plan view thereof;

FIG. 3 is a side elevation view thereof;

FIG. 4 is a bottom plan view thereof;

FIG. 5 is a perspective view of a second embodiment of a sealable snack container in an open position showing my new design;

FIG. 6 is a top plan view thereof;

FIG. 7 is a side elevation view thereof; and,

FIG. 8 is a bottom plan view thereof.

The broken line portion of the figure drawings is included to show unclaimed subject matter only and forms no part of the claimed design.
